UNITED STATES PATENT OFFICE.

RUSSELL I. RHODES, OF NORTH ATTLEBORO, MASSACHUSETTS.

BOX AND METHOD OF MAKING THE SAME.

Application filed June 5, 1925. Serial No. 35,093.

This invention relates to boxes and to a method of making the same and more particularly to boxes of the general type commonly employed, for example, to hold jewelry, silverware, confectionery, and other small, fragile, or valuable articles.

Goods of the character above indicated are commonly packed by the manufacturer directly in the boxes in which they are sold to the ultimate consumer and while the box is primarily intended as a shipping receptacle, and for this purpose must be cheap to construct, light in weight, and highly resistant to crushing in order adequately to protect its contents from injury, the retail trade and the ultimate consumer, demand in many cases (as for example when the enclosed article is intended as a gift), that such boxes be of highly ornamental character.

In order to enhance the appearance of such boxes, which are usually made of cardboard or similar material, covered with ornamental paper, silk, leather or velvet, they are frequently provided with upwardly convex covers, the convexity being produced by the insertion of padding between the top of the cover proper and the ornamental covering material, while the bottoms of the boxes as well as the covers are usually provided with "extensions", that is to say, the bottoms and covers extend outwardly in the form of flanges or lips beyond the sides of the boxes. The application of padding to the cover is a slow and expensive process while the production of extension edges requires a double thickness of material in the top and bottom and in most cases also necessitates hand operation.

In accordance with the present invention, I have devised a novel type of box and a method of making the same which enables the manufacturer to produce a box having extension edges and a top which simulates the hand made padded top without substantial waste of material and with substantially no more labor than is required in making a plain covered box. In the accompanying drawings a preferred form of the invention is illustrated by way of example, together with certain modifications thereof.

In the drawings,

Fig. 1 is a side elevation of a box constructed in accordance with the present invention;

Fig. 2 is a vertical section to larger scale on the lines 2-2 of Fig. 1;

Fig. 3 is a fragmentary section similar to that of Fig. 2, illustrating a modified construction;

Fig. 4 is another fragmentary section illustrating a still further modification;

Fig. 5 is a perspective view to small scale showing a strip of material adapted to form a side wall of one of the box parts; and

Fig. 6 is a plan view of a plate adapted to form the bottom of the box body or the top of the cover.

Referring to the drawings, the numeral 1 designates the improved box comprising a cover furnished with an extension edge 2 and a body or bottom portion having an extension edge 3.

In accordance with the present invention the first step in making the box consists in providing a pair of plates 4 (Fig. 6) of substantially equal size adapted to form the bottom of the box body and the top of the cover. These plates may be cut from suitable sheet material for example sheet steel, celluloid, etc. by a punching or stamping operation and are of a contour corresponding to that of the box to be made, that is to say, if the box be rectangular as herein shown, these plates will be rectangular in form, whereas if the box is to be of circular or other shape, the plates will be shaped correspondingly.

Either after or simultaneously with the cutting of these plates 4, their edges are turned up to form marginal flanges, as indicated at 5, having inner edges 6.

Referring more particularly to Fig. 2, the plate 4^a which forms the bottom of the box body is furnished with a marginal flange 5^a which is inclined inwardly and upwardly; similarly the plate 4^b which forms the top member of the cover is provided with an inwardly inclined downwardly directed flange 5^b, the material of which these plates are made being of such stiffness that these flanges 100 retain their shape after being formed. To provide an upwardly convex top for the cover, the plate 4^b is dished during the cutting or punching operation so that its outer surface is convex and its inner surface concave.

In the form of box herein shown the cover telescopes over the side walls of the body portion, although the reverse arrangement might be employed if desired and by slight 110 and obvious modifications hereinafter referred to, the outer surfaces of the walls

of the body and cover can be made to lie in the same plane.

In forming the side walls of the cover, a strip 7^b, Fig. 5, of suitable material such,

- for example, as cardboard, or metal or celluloid is provided, said strip being of a width substantially equal to the desired width of the side wall of the cover and of a length substantially equal to the peripheral extent of the inner edge 6^a of the flange 5^b. This strip 7^b may be scored at the points 8, provided the box is of angular contour, so that the strip can readily be bent at the proper points to permit it to be fitted within the edge of the flange 5^b. When so bent, the strip 7^b is seated within the space defined by the edge 6^a of the flange, the edge of the strip bearing against the inner surface of the plate 4^b.
- 20 A piece of sheet material C, for example, ornamental paper, leather, velvet or the like, and of proper shape is now placed upon the convex outer surface of the plate 4^b and if desired cemented directly thereto. The marginal portions of the piece of material are then carried over the outer surface of the flange 5^b to which it may be cemented and over the outer surface of the wall member. The edges of this covering material are then turned inwardly at the point 9 and laid smoothly against the inner surface of the wall member as indicated at 10. A piece 11 of suitable material is now applied to the inner surface of plate 4^b to give it a finished appearance. The sheet material C may be attached throughout its entire area to the parts with which it engages by means of any suitable adhesive, or if desired certain parts of it may be left free of attachment,—for example, it may be desired to omit the application of cement to that part of the covering material which is exposed to view, particularly if such material be of a delicate character such that its appearance might be injured by the application of adhesive.
- 30
- 35
- 40
- 45

In making the body of the box substantially the same steps are followed except that as a preliminary to assembling the wall member 7^a with the bottom member 4^a a spacer strip 12 is provided which is seated against the inner edge of the flange 5^a of the bottom plate 4^a. This spacer strip 12 may be formed of cardboard of suitable length and preferably of a width such that when its lower edge is seated upon the inner surface of the plate 4^a its upper edge will be flush with the upper edge of the flange 5^a. This spacer member is preferably of a thickness substantially equal to the thickness of the side wall of the cover and serves to space the side wall 7^a of the body of the box from the edge of the flange 5^a, to permit the wall of the cover to telescope over the wall of the body. This wall member 7^a is of any suitable width and extends around the entire

inner periphery of the spacer strip 12, to which it may be attached if desired by adhesive, although this is not necessary.

A piece of covering material 13, which may be similar to the covering material C or of different character or appearance as desired, is applied to the lower surface of the plate 4^a and its margins are extended up over the outer surfaces of the flange 5^a and the wall member 7^a and are then turned down inside of the wall member 7^a as indicated at 14, such portion of this covering as may be desired being cemented to the surface with which it engages. Suitable covering material 15 is then applied to the inner surface of the plate 4^a.

The covering material in each case thus forms a binder for holding the parts of the cover and of the box body respectively in proper assembled relation and it will be observed that the cover consists of but two elements in addition to the covering material while the box body comprises but three elements, namely, the bottom plate, the spacer, and the side wall, in addition to the sheet of covering material.

While the box parts thus consist of a minimum number of elements, the box has the external appearance of an extension edge padded top box of expensive character, although it may be made at extremely low cost. At the same time since the top and bottom plates may readily be made of very strong material such, for example, as sheet steel, sheet celluloid or the like the box is capable of withstanding heavy crushing strains without breaking and without danger of injury to its contents. Obviously, the side walls of the box and cover may be made of material similar to that of the top and bottom plates if desired, although under ordinary circumstances, cardboard provides sufficient strength at this part of the box and is preferable in some instances by reason of the ease with which the covering material may be cemented thereto.

The box thus formed is very light in weight while the method of procedure herein outlined is applicable to boxes of substantially any shape and size. Such boxes moreover, may be made of much greater depth than would be possible by punching or stamping operation in which the side walls of the box are made integral with the top and bottom, since in accordance with the latter process, the depth of the side walls is limited by the capability of the sheet material to flow without rupture between the dies.

In Fig. 3, a modified arrangement is shown, in which the bottom plate 14' is provided with a marginal flange 15' projecting upwardly substantially at right angles to the plane of the plate proper. A spacer strip 16 is seated against the surface of the flange

15 and a wall strip 17 fits against the inner surface of the spacer. The bottom plate, spacer and wall strip are held in assembled relation by the covering material 18 which 5 conceals the under surface of the plate 14' and extends upwardly over the outer surface of the flange and wall member and down against the inner surface of the latter. The upper face of the bottom plate 14 may 10 also be covered with suitable sheet material 19 of any desired character.

In this case the extension edge is not so pronounced as in the first case and in fact if the wall member of the corresponding 15 cover, not shown, be of suitable thickness, the outer face of the cover will lie in the same plane as the outer surface of the bottom portion of the box body, which may be found desirable under some circumstances. 20 In Fig. 4, a further modification is illustrated in which the bottom plate 24 is furnished with a curved upstanding marginal flange 25. A spacer 26 and wall member 27 are held in proper assembled relation 25 with the plate 24 by means of the covering material 28. The inner surface of the plate 24 may also be concealed by means of suitable covering material 29.

While Figs. 3 and 4 show modified constructions of the box body only, it is obvious 30 that the cover may be made to have a corresponding external appearance if desired, while it is also clear that the same general mode of manufacture herein disclosed is applicable to boxes having flat, concave or intricately embossed covers.

I claim:

1. That method of making a box part having an extension edge which comprises 40 providing a plate of stiff and strong sheet material having a bent marginal flange whose inner edge has a contour of substantially the desired shape and size of the outer surface of the side wall of said box part, arranging a wall member within said flange, applying a sheet of covering material to the outer surface of the plate and to the outer face of said wall member, turning the edges of said covering sheet in over the edges of 45 said wall member, and cementing the in-turned edges of the covering material to the inner surface of said wall member.

2. That method of making boxes which comprises forming a plate from strong and 55 stiff sheet material, said plate having a bent marginal flange, preparing a strip of sheet material of a thickness substantially equal to the desired thickness of the box wall, of a width substantially equal to the 60 distance between the free edge of the flange and the inner surface of the plate, and of a length equal to the peripheral extent of the inner edge of the flange, setting such strip on edge within the flange, preparing a 65 second strip of sheet material of desired

width and proper thickness to form the box wall, and of a length substantially equal to the peripheral extent of the inner surface of the first strip, setting said second strip on edge within the first strip, and binding said strips in place by means of a sheet of covering material adhering to the strip and covering the outer surface of the plate. 70

3. That method of making a box cover which comprises forming a plate from thin, 75 stiff and strong sheet material, said plate being upwardly convex and having a depending marginal flange, preparing a strip of stiff sheet material of a length substantially equal to the peripheral extent of the inner 80 edge of the flange of the plate and of a width substantially equal to the desired depth of the cover wall, placing such strip on edge within the flange of said plate, applying a covering sheet to the convex 85 surface of the plate and to the outer surface of the strip and securing the covering sheet to the strip.

4. That method of making covered boxes which comprises providing two plates of stiff 90 sheet material of the same size and each having an inwardly bent marginal flange, preparing strips of stiff sheet material of proper width to form the walls of the box body and cover respectively, arranging the respective 95 strips on edge within the marginal flanges of the respective plates, inserting a spacer to space the strip which is to form the wall of the box body from the inner edge of its flange by a distance substantially equal to the thickness of the strip forming the wall of the cover, and binding the cover and body wall strips to their respective plates by means of sheet material covering the outer faces of the plates and cemented to the respective strips. 100

5. A box part comprising a thin stiff plate having a bent marginal flange, a vertical wall member disposed within the inner edge of the flange, and a piece of sheet material extending over the outer surface of the plate 110 and the outer surfaces of the flange and wall member and adhering to the latter to hold the plate and wall member in assembled relation.

6. A box body comprising a flat bottom plate of thin stiff sheet material having an inwardly and upwardly inclined marginal flange, a strip of sheet material of a length substantially equal to the peripheral extent of the inner edge of said flange and of a 115 width substantially equal to the distance between the edge of said flange and the inner surface of the bottom plate, said strip standing on edge on said inner surface and bearing against the flange, a wall of sheet material 120 of a width equal to the desired depth of the box body standing on edge on the inner face of the bottom plate and bearing against the inner surface of the spacer strip, and a piece 125 of sheet material covering the outer surface 130

of the bottom plate, its flange, and the outer and inner surfaces of the wall member and binding the parts together.

7. An extension edge box cover having a convex upper surface and a concave inner surface consisting of one piece of sheet metal, a strip of cardboard forming the side wall of the cover disposed with its edge against the inner surface of the top plate, and a sheet of decorative covering material for binding the top member and wall strip together.

8. A box cover comprising an upwardly convex top plate of thin stiff material having a downwardly and inwardly directed marginal flange, a strip of sheet material constituting a wall member bearing against the inner edge of said flange, and a piece of sheet material covering the upper surface of the top plate and the outer surface of the flange and wall member, and having its inner margin turned over against the inner surface

of the wall member and cemented thereto.

9. A box having a cover and a body, the top member of the cover and the bottom of the body being of equal size and each consisting of a plate of sheet metal having an inwardly directed marginal flange, wall members for the cover and body respectively each wall member consisting of a strip of cardboard of suitable width, the wall member for one of said parts being spaced inwardly from the inner edge of the flange of its respective metal plate and the wall member of the other part bearing directly against the inner edge of the flange of its respective plate, and sheet material binding the wall members to their respective plates and covering the outer surfaces of the wall members and plates.
